UNITED STATES PATENT OFFICE.

FRED P. BUTMAN, OF HOLBROOK, ASSIGNOR TO HIMSELF AND EDWARD H. FENNESSY, OF NEWTON, MASSACHUSETTS.

STOCKING-SUPPORTER.

SPECIFICATION forming part of Letters Patent No. 372,401, dated November 1, 1887.

Application filed August 18, 1887. Serial No. 247,303. (No model.)

To all whom it may concern:

Be it known that I, FRED P. BUTMAN, a citizen of the United States, residing at Holbrook, in the county of Norfolk and State of Massachusetts, have invented certain Improvements in Stocking-Supporters, of which the following is a full, clear, and exact description, reference being had to the accompanying drawings, making part of this specification, in which—

Figure 1 is a perspective view of my improved stocking-supporter applied to the leg of a wearer. Fig. 2 is a side elevation of the supporter. Fig. 3 is a section on the line *xx* of Fig. 2. Fig. 4 is a plan of the adjustable fastening-plate detached.

My invention has for its object to provide a neat and effective stocking-supporter, which can be easily and quickly adjusted to the length of stocking and size of limb of the wearer; and my invention consists in the combination, with the strap or piece of webbing which encircles the leg of the wearer, of a fastening plate or holder having a transverse slot and a diagonal slot, through which the webbing passes and by means of which the pendent portion, to which the stocking is attached, is held securely at a right angle to the leg-encircling portion, and made adjustable in length, as hereinafter more particularly set forth.

My invention also consists in certain combinations of parts and details of construction, as hereinafter set forth and specifically claimed.

In the said drawings, A represents a strap or single continuous piece of elastic webbing of sufficient length to form both the portion *b*, which encircles the leg of the wearer, and the pendent portion *c*, to the lower end of which is secured a clasp, *d*, or other suitable attaching device, adapted to engage with and hold the upper edge of the stocking, as seen in Fig. 1.

B is an ornamental sheet-metal plate or holder, of the form shown, one end of which is provided with two transverse slots, *e f*, through which one end, 5, of the webbing A is passed in the manner shown, whereby it is held securely in place and made adjustable to

vary the length of the leg-encircling portion *b* by drawing it through the said slots *e f* in a well-known manner. At the opposite end of the plate *B* is a single transverse slot, *g*, and extending diagonally across the plate *B* at an angle of about forty-five degrees is a slot, *h*.

The strap or webbing A passes up through the slot *g*, thence over the outer face of the plate *B* and down through the diagonal slot *h*, and by means of this diagonal slot *h* the end of the strap which forms the pendent portion *c* is caused to assume a position at right angles to the leg-encircling portion *b* and within the encircling portion, whereby the leg of the wearer is protected against any abrasion from the edge of the plate, and the pendent portion *c* is readily adjustable, having to be drawn through only two slots instead of three, as shown in former patents, the two slots *g h* causing it to be held securely in place without liability of slip when the supporter is on the leg of the wearer, while the webbing can be easily slid through these two slots *g h*, to vary the length of the pendent portion *c* in accordance with the length of the leg of the stocking worn, and after the length of the pendent portion *c* has been adjusted the length of the leg-encircling portion *b* may be varied independently of the pendent portion by sliding the end 5 of the webbing A within the slots *e f*, thereby adjusting it to fit the smaller portion of the leg below the knee comfortably, and without requiring any compression to hold it in place, thus insuring freedom of action to the cords and muscles of the leg, while if the attaching device at the end of the pendent portion *c* should accidentally become unfastened from the upper edge of the stocking the leg-encircling portion *b* would remain in place upon the leg, without slipping down thereon.

The above-described stocking-supporter has no sharp points, corners, edges, or projections to wear and tear the clothing, as the plate or web-holder *B* lies smoothly against the inner flat portion of the leg immediately beneath the knee, while the diagonal slot *h* insures the pendent portion *c* being always in a proper position for use, and, in connection with the trans-

verse slot *g*, affords a simple and convenient means of adjustment, as before described.

I am aware that a slotted plate for a stocking-supporter is not broadly new, and I do not 5 claim such as my invention, the same being shown in the patent to Anderson, No. 245,761.

What I claim as my invention, and desire to secure by Letters Patent, is—

In a stocking-supporter, the combination, 10 with a strap or piece of webbing which encir-

cles the leg of the wearer, of a fastening-plate B, provided with transverse slots *e*, *f*, and *g* and a diagonal slot, *h*, substantially as and for the purpose described.

Witness my hand this 15th day of August, 15
A. D. 1887.

FRED P. BUTMAN.

In presence of—

P. E. TESCHEMACHER,
F. V. HAYDEN.
